(21) Appl. No.: **29/129,548**

CLAIM

(22) Filed: **Sep. 18, 2000**

The ornamental design for a circuit pattern of belt tension device sensor bar, as shown and described.

(51) LOC (7) Cl. **13-03**

DESCRIPTION

(52) U.S. Cl. **D13/182**

The single FIGURE is a front elevational view of a circuit pattern of belt tension device sensor bar showing my new design.

(58) Field of Search **D13/182, 110, D13/123, 133, 199; 27/829, 830, 831, 832, 846; 174/250, 251, 253, 254, 255, 260, 261, 268; 361/718, 748, 752, 753, 760, 783, 784, 820**

The outline of belt tension device sensor bar shown in broken lines in the figure is for illustrative purpose only and forms no part of the claimed design.
